UNITED STATES PATENT OFFICE.

DANIEL O. LAWRENCE, OF SIXTEEN, MONTANA, ASSIGNOR OF ONE-THIRD TO C. J. GARLOW, OF COLUMBUS, NEBRASKA, AND ONE-THIRD TO T. J. COTTINGHAM, OF LOS ANGELES, CALIFORNIA.

PAY-STATION INSTRUMENT.

1,142,333.

Specification of Letters Patent.

Patented June 8, 1915.

Application filed June 13, 1913. Serial No. 773,495.

To all whom it may concern:

Be it known that I, DANIEL O. LAWRENCE, a citizen of the United States, residing at Sixteen, in the county of Meagher and State 5 of Montana, have invented certain new and useful Improvements in Pay-Station Instruments, of which the following is a specification.

My invention relates to slot machines and 10 particularly to a slot machine adapted to be used at a telephone pay station and provided with means for transmitting to the central office information as to the denomination of the coin deposited in the pay station instrument.

My object is to construct such an instrument which will be infallible in operation and very simple for the user thereof to operate.

Another object of my invention is the construction of an instrument such as the above which is adapted to transmit an electrical impulse or a series thereof to the central office at which place said impulses affect 25 a suitable indicator, the number of said impulses varying with the denomination of the coin deposited.

Another object of my invention is to provide such an instrument which may be operated from one point no matter what the denomination of the coin may be.

A still further object is the production of a machine such as that above set forth which cannot be operated except when a coin of 35 standard size has been deposited in the proper slot.

With the foregoing and other objects in view my invention consists of such details of construction and in the arrangement and 40 combination of parts as will be hereinafter more fully described and specifically pointed out in the appended claims.

In describing my invention in detail reference will be had to the accompanying 45 drawings wherein like characters denote like or corresponding parts throughout the several views and in which:—

Figure 1 is a view in front elevation of my invention, a part of the casing thereof 50 being broken away to show the interior construction; Fig. 2 is a vertical sectional view taken on the line A—A of Fig. 1; Fig. 3 is a sectional detail view of one corner of the casing showing one slot cast integral there-

with; Fig. 4 is a sectional view of a portion 55 of my invention showing the method of transmitting motion from the plunger to the interior mechanism; and Fig. 5 are details disclosing more fully the operation of the contacts by means of the fibrous disks.

In carrying my invention into practice I provide a casing 1 of suitable size, said casing having slots 2, 3, 4, 5 and 6 at the front portion thereof and extending from the upper edge on the top to near the bottom of 60 the inner face of the front, said slots being graduated in size to receive five cent pieces, ten cent pieces, twenty-five cent pieces, one-half dollars and dollars respectively. Guards 65 may be formed on the casing at the upper ends of the slots in order to facilitate insertion of the coin, these guards being shown in the drawings at 7, 8, 9, 10 and 11. It will be noted that the interior walls of the slots are provided with apertures 12, 12', 13 and 70 14, the first two mentioned being disposed near the top of the slots and the last two 75 near the bottoms thereof.

Journaled in opposite ends of the casing and extending from end to end thereof approximately parallel to the front and back walls is a shaft 15, said shaft having fixed upon it at suitable intervals a number of non-conducting disks 16, 17, 18, 19 and 20 which disks may be made out of wood fiber 80 or similar material. On the peripheries of said disks are formed notches 21, disk 16 being provided with one notch, 17 with two notches, 18 with three notches, and so on, each successive disk having one more notch 85 in its periphery. The purpose of these notches will be readily apparent after a further disclosure of the operation of my invention.

The shaft 15 may be partially rotated by means of a plunger 22 extending through the top of the casing and guided through a projecting arm 23 in the interior thereof, a spring 24 being disposed between said arm and a collar 25 on said plunger whereby the plunger will be returned to its normal position after pressure is withdrawn. The lower end of the plunger 22 is pivoted to a short arm 26, the latter being fixed to the shaft 15, said lower end of the plunger being held 100 between the bifurcated end of the arm by means of a pin 27 which is slidable in a slot 28 formed in said arm. Suitably mounted 105

in said casing and extending horizontally across the interior thereof slightly below the shaft 15, is an arm 29 to which is pivoted a trap 30 the pivot being accomplished by connecting the trap with a shaft or pivot pin having a pivotal connection in the arm and in the drawings designated as 33 which is located approximately midway between the opposite end of said trap which opposite ends are bent angularly to form arms 31 and 32 which are adapted to alternately contact the front walls of the coin slots by passing through the apertures 12 and 14 respectively in the rear walls of said slots. 10 Another arm 34 is fixed to the trap 30 at its pivotal point so as to extend at an acute angle to said trap. Fixed on the shaft 15 and extending upward therefrom is a lever 35 which is pivoted to one end of a link 36, 20 the latter being in turn connected to the free end of the afore-mentioned arm 34 by means of a pin 35 operative in an elongated slot 38 in said link. The outer end of the arm 34 is connected to the end of the arm 29 by 25 means of a spiral spring 39, the parts being arranged in such relation to one another that the trap will be "snapped" from one of its positions to the other position as soon as the plunger 22 and the co-acting mechanism 30 moves the path about its center of oscillation thereof.

The numeral 40 indicates a leaf spring which is provided with a struck-out portion or projection 41, which it will be noted upon 35 reference to the drawings, is adapted to enter the notches 21 in the fibrous disks before mentioned. The upper end of said spring is bent angularly forward and downward and provided with a contact point 42. Said 40 spring is fastened to the casing at a point 43 between the apertures 13 and 14, a layer of insulation being interposed between the spring and the casing for obvious reasons. A wire 45 forming a portion of an electrical 45 circuit leading to the central office is connected to the spring 40 at 43.

Co-acting with this spring is a second leaf spring 47 which is pivoted in any suitable manner as at 46, said last mentioned 50 spring extending upward within the angularly bent end of the spring 40 and provided with a contact point 48 similar to the point 42, said points being opposed to one another. The lower end 49 of this spring is 55 slightly bent so as to project through the aperture 13 into the coin slot. The other conductor of the afore-mentioned circuit may be connected to the spring 47 as shown at 50.

60 For the purpose of preventing more than one coin being inserted in a slot at the same time I have provided a second trap near the upper portion of the casing. This trap consists of arms 51 to which is pivoted an 65 angularly bent member 52 which is adapted

to project through the apertures 12', other arms 53 being connected to said member in such manner as to project through the aperture 12. It is thought that the operation of my invention will be readily apparent 70 from the foregoing description.

The operation of this device is as follows: Assuming that a five cent piece is to be inserted in the slot 2 it will be seen that said five cent piece will fall downward until it 75 contacts the arm 31 of the trap 30 which, of course, is in its normal position. Before coming to rest on said arm, however, the coin will contact the arm 53 of the trap 52, and will pivot said trap upon its mounting 80 in such manner that the upper arm thereof will close the upper end of the slot so as to prevent another coin being inserted. The operator then presses downward upon the plunger 22 which partially rotates the shaft 15 and its co-acting mechanism and "snaps" 85 the trap 30 about its center of oscillation so that the coin will fall in the slot until it comes to rest upon the arm 32 of the trap which has now entered the aperture 14 in 90 the slot. At the same time it will be seen that the coin rests against the inwardly bent end 49 of the spring 47, so that said spring is swung on its pivot a short distance so that the contact point 48 moves nearer to the 95 contact point 42. When the pressure on the plunger 22 is now removed the spring 40 returns the parts to their normal positions, thus causing the projection 41 on the spring 40 to fall into the notch 21 in the periphery 100 of the disk. This allows the contact point 42 to make connection with the opposed point 48 whereupon an electric circuit is closed and an impulse shot through the conductors to the central office where it is registered by a proper indicator. It will be understood that this impulse is merely momentary and at the following instant the disk 16 has revolved to such an extent that the contact points are again separated. It 105 will be seen that when a coin is placed in one of the other slots there will be as many impulses sent through the conductors as there are notches in the periphery of the 110 disk corresponding to the slot in which the coin has been dropped. It will also be seen that although all of the disks revolve, no matter what the denomination of the coin may be, only that disk corresponding to the 115 slot in which the coin is located will cause an electric impulse to be passed through the circuit, for none of the contact points will meet except when the coin is resting against the downwardly bent end 49 of one of the 120 springs 47. As soon as the pressure of the plunger 22 is released the spring 40 causes the parts to assume their normal positions whereupon the coin will drop into the space 125 55 in the lower part of the casing.

It is thought the operation and construc-

tion of my invention will be readily understood from the foregoing.

I desire to point out that slight changes in construction and in the arrangement and combination of parts may be resorted to without deviating from the spirit of my invention provided such changes fall within the scope of the appended claims.

Having thus fully described my invention what I claim as new and desire to secure by Letters Patent is:—

1. In a slot machine, a casing, a shaft journaled therethrough, a disk element fixed upon the shaft, notches in the periphery of said disk, a spring member, a struck out portion on said spring member adapted to normally engage the periphery of said disk and to fall into the notches thereof as the disk may be turned, a second spring member adapted to be contacted by said first spring member whereby an electrical circuit is closed, a coin slot adapted to have a coin inserted thereinto, a stop in said slot positioned to halt the progress of the coins therethrough and adapted to be manually moved from the operative relation to permit further movement of the coin within the slot, said second spring member having a portion thereof extended into said slot, and a second stop positioned to become operative upon movement of said first stop to the inoperative position to hold the coin at a point within the slot in engagement with said second spring member whereby the electrical circuit is closed.

2. A slot machine comprising a casing having a slot therein, a shaft journaled in said casing, a disk fixed upon said shaft to be capable of revoluble movement therewith, said disk having a notch in the periphery thereof, a spring mounted within said casing and having a projection normally bearing against the periphery of said disk and adapted to enter said notch, a second spring mounted within the casing to be normally held from contact with said first spring and having a portion thereof projected into said coin slot, means to prevent normal free movement of a coin through the slot and to be capable of manual operation to allow movement of the coin to a position to contact with said second spring member, and all of said parts so arranged that the contact point to be contacted by said first spring member causes movement of this member to a point to be contacted by said first spring member as the projection thereof enters the notch of said disk and to thereby establish an electrical circuit, and means for rotating said disk to cause movement of the projection into and from said notch.

3. A slot machine comprising a casing having a slot therein, a shaft journaled in said casing, a disk fixed on said shaft, said disk having a notch in the periphery there-

of, a spring having a projection adapted to enter said notch, a second spring adapted to be contacted by a coin in said slot, said springs adapted to meet when said projection enters the notch in said disk and when said coin contacts the second mentioned spring whereby an electric circuit may be closed, and means for rotating said disk.

4. A slot machine comprising a casing having a number of coin slots placed at proper points therein, a shaft journaled in said casing, a plurality of disks mounted on said shaft and provided with notches therein, the number of notches in the several disks being varied, spring members normally bearing against the notched peripheries of said disks, a second set of springs pivoted to the casing and adapted to be moved into contact with said first-mentioned spring, said second set of springs located to project within the coin slots and to be swung to a position closely adjacent said first spring upon the insertion of a coin into said slot, and means for rotating said shaft and said disks to cause contact between the spring members of said first and second sets.

5. In a slot machine, a casing, a coin slot provided at a suitable point in said casing, a shaft revolvably mounted in said casing, a disk on said shaft having notches in the periphery thereof, a spring member, a struck-out portion intermediate the end of said spring member adapted to normally engage the notched periphery of said disk, said spring member having an angularly bent overhanging end, a contact point near said end, a second pivoted spring member carrying a contact point at one end adapted to be engaged by contact of said first spring member and having an end thereof projecting into the coin slot to be engaged by the coin inserted into the slot and thus be swung to a position closely adjacent the contact of said first spring member, and means to cause movement of said disk to permit movement of the struck-up portion of said first spring member into the notches thereof and to thus allow engagement of the contact point of said two spring members.

6. A slot machine comprising a casing, a coin way in said casing, a shaft journaled through said casing, a disk fixed on said shaft to be capable of rotation therewith, a trap pivoted in said casing, an offset portion at each end of said trap and said offset portions adapted to close said coin ways at different stages during the operation, a spring contact member engaging with the periphery of said disk in a manner to have motion transmitted thereto by turning of the disk; a second contact member mounted adjacent said spring contact and having a portion thereof extended into said coin way, means to rotate said disk, means to tilt said trap, and all of said parts so arranged that operation

115

120

125

130

of the trap permits the coin to move to a position of engagement with said second contact member and rotation of the disk causes said first contact to have movement into and out of bearing contact with said second contact with the parts in the relation as hereinbefore set forth.

7. In a slot machine, a casing, a shaft journaled to the same, a plurality of coin slots located in the casing at predetermined spaced apart points, disks on said shaft mounted at points corresponding to the location of said slots, a plunger slidable in said casing, an arm on said shaft having a slot therethrough, a pin carried by said plunger to be received through said slot, a bracket member mounted within the casing, a trap pivoted on said member, said trap having offset portions at each end thereof, said offset portions positioned to engage a coin inserted in the slot of said casing, an arm connected to said shaft, an arm secured on said trap, and a link connected between said arms in such relation that when the plunger is depressed the connection thereof with the slotted arm secured on the shaft

will cause the shaft to be rotated and simultaneously the trap will be swung by the connection thereof.

8. A slot machine comprising a casing having a plurality of slots therein, a plurality of springs arranged in pairs corresponding to said slots, said springs adapted to close electric circuits, a shaft journaled in said casing, means on said shaft whereby said springs are permitted to come in contact with one another when a coin is resting against one of said springs, means for rotating said shaft, a trap pivoted in said casing, arms extending from said trap and adapted to be moved so as to regulate the passage of a coin through the slots, said trap being actuated to have swinging movement around its point of pivot by the operation of the shaft-rotating means, and means for restoring the parts to their normal positions.

In testimony whereof I affix my signature in presence of two witnesses.

DANIEL O. LAWRENCE.
